[57] CLAIM

The ornamental design for a folding cribbage board, as shown and described.

DESCRIPTION

FIG. 1 is a plan view of the folding cribbage board, showing my new design, showing the inside of the lid, shown broken away for ease of illustration;

FIG. 2 is a plan view of the inside of the base;

FIG. 3 is a top plan view of the entire board, shown in the closed position;

FIG. 4 is a bottom plan view thereof;

FIG. 5 is a reduced top plan view thereof, shown in the open position;

FIG. 6 is a rear elevational view thereof, shown in the closed position;

FIG. 7 is a front elevational view thereof;

FIG. 8 is a right side elevational view thereof, the left side being a mirror image thereof;

FIG. 9 is a perspective view thereof;

FIG. 10 is a front elevational view of the board, shown in the open position;

FIG. 11 is a rear elevational view thereof; and,

FIG. 12 is a reduced right side elevational view thereof, the left side being a mirror image thereof.
